CLAIM

The ornamental design for a game layout, as shown and described.

DESCRIPTION

FIG. 1 is a front right perspective view of a game layout showing our new design;

FIG. 2 is a front left perspective view thereof;

FIG. 3 is a rear left perspective view thereof;

FIG. 4 is a rear right perspective view thereof;

FIG. 5 is a front elevational view thereof;

FIG. 6 is a rear elevational view thereof;

FIG. 7 is a top plan view thereof;

FIG. 8 is a right side elevational view thereof; and,

FIG. 9 is a left side elevational view thereof.

(Continued)

The broken line portions of the game layout form no part of the claimed design.

1 Claim, 8 Drawing Sheets
